UNITED STATES PATENT OFFICE.

ELMER M. FELL, OF SPRINGFIELD, MASSACHUSETTS.

RADIATOR-SUPPORT.

SPECIFICATION forming part of Letters Patent No. 360,869, dated April 12, 1887.

Application filed December 15, 1886. Serial No. 221,613. (No model.)

To all whom it may concern:

Be it known that I, ELMER M. FELL, a citizen of the United States, residing at Springfield, Hampden county, State of Massachusetts, have 5 invented a new and useful Improved Radiator-Support, of which the following is a specification.

My invention relates to that class of support for the feet of radiators and stoves having for 10 its object the preservation of the carpet or other covering for the floor, by rendering it unnecessary to cut or remove a piece from said covering in spreading it to inclose the base or feet; and the invention consists in the combination 15 and construction as hereinafter described, and more particularly pointed out in the claims.

My invention is fully illustrated in the accompanying drawings, in which—

Figure I is a full-size end elevation of my 20 device. Fig. II is a side elevation. Fig. III is a top plan view. Fig. IV is a section in plan on the dotted line $\alpha\alpha$ of Fig. I. Figs. V, VI, VII, VIII, IX, and X are detail views of a modification, of which Fig. XI is a complete 25 view of said details assembled, and Fig. XII is a view of my device combined with a radiator.

B is a base, adapted to rest immediately upon the floor and be secured thereto by screws passing through the holes b.

30 C is a top, upon which the radiator foot or base immediately rests. The surface of top C is roughened, as shown, to prevent the radiator from slipping thereon, and spurs c, rising at right angles to said surface and disposed upon 35 its perimeter, still further prevent any displacement of the radiator.

Connecting the base B and top C, and in effect integral with both, is a web, D, long enough to supply ample strength to the support, and in cross-section comparatively narrow, as seen in Fig. IV, and beveled away on 40 each end to form an edge in elevation.

In operation, the base B, securely bolted to the floor, is covered by the carpet, and the configuration of the web D permits the outside edges of each strip to be brought upon each side of the web, to be brought together at each end of the web without leaving any folds or wrinkles in the even surface of the carpet, 45 and said configuration of web D permits a simple slit in the carpet, where the support would 50 not come opposite a seam therein, to suffice to adapt the carpet to cover the base B of the support.

Heretofore radiators have required, when 55 placed in the center of apartments or at any distance from the walls thereof, that pieces of the carpet should be removed to seat them upon the floor, which mutilation is a great injury to a carpet which may have to be changed in the 60 same room or removed to others.

In Fig. XI my device is shown built up of sections, divided as follows: The base B, having the web D solid therewith, has a flat surface at the top of the web, in which, coincident 65 with the length of the web, a dovetail groove, d, is sunk, open at one end, and having a screw-socket, e, at its mouth. Into the groove d fits a corresponding rib or cleat, f, upon a section, E, having a shoulder upon each side of its cleat 70 adapted to conform to and rest upon the top of section B when the cleat is slid into the groove d. The part E has a screw-hole in the end of its cleat coinciding with the base, and a screw fastens the 75 two sections. The section E has a roughened upper surface, and centrally sunk in said surface is a screw-socket, g. The other section, which, with the one E, forms in effect the section or part C of Fig. I, and lettered F in Fig. 80 XI, consists in a plate adapted to rest upon the corresponding surface of part E and be secured thereto by a screw passing into socket g through an opening, i. The upper surface of plate F is roughened, as shown, and the 85 spurs c rise therefrom. The section B may be leveled and screwed to the floor and have the carpet drawn around it without the interference of the projecting flange formed by the top of the "support," and when the radiator is removed for the summer the section B may be 90 left in place, to facilitate the replacing of the radiator without being itself in the way. When the section B is adjusted to the radiator and combined with the carpet, the sections E and 95 F, which may be in one, may be combined with section B, to complete the support; but by forming the section F adjustable upon the one E, as shown, the one F may be turned before being finally clamped, to present its spurs c 100 in the most favorable position to hold the feet of different radiators from slipping.

I am aware that a support has been made to extend from the wall to hold up radiators, while adapted to facilitate its being covered upon one side by the carpet, and I make no claim thereto.

Without a departure from the spirit of my invention, the groove *d*, in place of being in the top of the web, as shown in the drawings, may be placed in the base, and the cleat *f* formed upon the bottom of the web, by means of which, when the rest of the support is taken away, the base in position may be covered completely by the carpet until it is desired to set up the radiator.

Now, having described my invention, what I claim is—

1. The within-described improved support for stoves and radiators, consisting of a top, *C*, having a flat upper face provided with retaining-spurs *c* upon the perimeter of said surface and at right angles thereto, a base, *B*, of the form of a frustum of a cone or pyramid and perforated to form screw-holes for securing it to the floor, and a web, *D*, surmounting the base, supporting the top *C*, and joined to both, and in configuration having a reduced diameter relative to that of the top and base, and having wedge-shaped opposite ends, all combined and arranged as and for the purpose set forth.

2. In supports for radiators, a base, *B*, of the form approximately of a truncated cone or pyramid and provided with screw-holes *b*, a web, *D*, arranged upon top of the base and integral therewith, having wedge-shaped ends 35 and provided upon top with a groove, *d*, and socket *e*, and a top, *C*, having a flat bearing-surface and spurs *c* upon the perimeter thereof, a cleat, *f*, and screw-hole corresponding with socket *e*, all arranged as set forth.

3. In radiator supports, the combination of a base, *B*, in the form of a truncated cone or pyramid and provided with screw-holes *b*, a web, *D*, of reduced dimension in one direction relative to the base *B*, with beveled ends 45 having a groove, *d*, and socket *e*, and arranged to surmount said base, a plate, *E*, provided with cleat *f*, screw-hole corresponding with socket *e* and with socket *g*, and plate *F*, provided with spurs *c* upon its perimeter, and so with screw and screw-hole opposite the socket *g*, all arranged to operate as and for the purpose set forth.
